(57) **CLAIM**

We claim the ornamental design for a shackle, as shown and described.

DESCRIPTION

FIG. 1 is an isometric perspective view showing a shackle embodying the new design;

FIG. 2 is an isometric perspective showing the opposite side of the shackle embodying the new design shown in FIG. 1; FIG. 3 is a plan front view of the shackle of FIG. 1; FIG. 4 is an opposite side elevation view of the shackle of FIG. 3;

FIG. 5 is another side view of the shackle of FIG. 1;

FIG. 6 is an opposite side view of the shackle of FIG. 5;

FIG. 7 is a top view of the shackle of FIG. 1;

FIG. 8 is a bottom view of the shackle of FIG. 1; and, FIG. 9 is an exploded isometric perspective view of the shackle of FIG. 1.

The broken lines are included for the purpose of illustrating environmental subject matter and form no part of the claimed design.

1 Claim, 7 Drawing Sheets
